UNITED STATES PATENT OFFICE.

JOHN BRIERLY, OF BROOKLYN, NEW YORK.

VALVE-GEAR FOR STEAM-ENGINES.

SPECIFICATION forming part of Letters Patent No. 235,410, dated December 14, 1880.

Application filed May 21, 1880. (No model.)

To all whom it may concern:

Be it known that I, JOHN BRIERLY, of the city of Brooklyn, in the State of New York, have invented a new and useful Improvement 5 in Valve-Gearing for Steam-Engines, of which the following is a specification.

In the accompanying drawings, Figure I represents a front view of the valve-gearing, some of the parts being shown in section. Fig. 10 II is a side elevation of the same.

Similar letters represent similar parts.

A represents part of a steam-cylinder and slide-valve casing, arranged vertical above the shaft D and supported by a suitable frame, B. 15 L is the usual D-valve on the port-face of the cylinder, moved by the valve-rod M working through the stuffing-box and in guide N.

The valve-rod M is connected through the stud-pin q to a disk, R, placed eccentrically to 20 the center of said disk R. Around the disk R a strap, S, is placed, connected to the rod T. At the lower end of this rod T a roller, Y, is attached, working in a suitable cam-groove, Y', in the cam-disk Z, attached to the 25 shaft D.

The eccentric-disk R is provided with an external plate or flange, R', provided with a suitable handle, H', and also with a stud-pin, A', to which a rod, B', can be attached. The 30 lower end of this rod B' is supported at the end of a lever, C', turning on a fixed center, D'. To this lever C' a roller, E', is attached, working in a suitable groove, F', (shown in dotted lines in Fig. II,) in the cam-disk Z'.

The grooves Y' and F' in their respective disks Z and Z' are nearly of the same shape and construction, and the disk Z' is placed upon the shaft D in relation to the disk Z, so that the center of the cam-groove F', which 35 operates the rod B', will be either about one-quarter of a circle or about forty-five degrees in advance or behind the center of the cam-groove Y', which operates the rod T, according to the motion of the crank-shaft.

To the disk-flange R' an eccentric-lever, G', is attached, acting upon the strap S whenever required, so as to lock the eccentric-disk R and the strap S firmly together.

The lower end of the rod T is supported on 50 the end of the lever C, turning on the fixed center D'. The lever C, which supports the rod T, and the lever C', which supports the

rod B', act at the same time, so as to keep the respective rollers Y and E' in their proper position.

When the rod B' is disconnected from the stud-pin A' and the strap S firmly connected to the eccentric-disk R by means of the eccentric-lever G', as above mentioned, the rod T, eccentric-disk R, and valve-rod M will form a rigid connection, and the full throw of the cam Y' will be communicated to the D-valve L, and the operation of this slide-valve will be in the regular manner, as if a straight connection were made between the cam and said valve.

To work expansively the strap S and eccentric-disk R are disconnected and the rod B' is connected to the stud-pin A', when the cam Y' will operate, through the rod T, the disk R, and the cam F' will act, through the rod B', upon the stud A', attached to the flange R' of said disk R, and as the pin q on said disk R is eccentric to said disk and between the center of the disk R and the center of the pin A', this combined action will produce a diminished motion on the pin q, and consequently on the valve-rod M and valve L.

It will readily be seen that this combined motion on the rod M, and consequently of the valve L, can easily be changed and regulated by the relative position of the stud-pin A'.

When the rod B' is thrown out of gear and the eccentric-disk R is unlocked from the strap S, the rod M, and consequently valve L, can be reversed and moved by hand by means of the reversing-lever H'.

What I claim as my invention, and desire to secure by Letters Patent, is—

1. In combination with the valve-rod M, the eccentric-disk R, with rod T, operated by a suitable cam, Z, and the rod B', operated by a suitable cam, Z', the whole being arranged and combined to operate substantially in the manner and for the purpose described.

2. In combination with an eccentric-disk R, and strap S, connecting the rod T to said eccentric-disk R, the locking-lever G, arranged to operate substantially as and for the purpose set forth.

JOHN BRIERLY.
